UNITED STATES PATENT OFFICE.

LOUIS KOOPERSTEIN, OF NEW YORK, N. Y., ASSIGNOR TO WEST DISINFECTING COMPANY, OF NEW YORK, N. Y., A CORPORATION OF NEW YORK.

SOAP-DISPENSING APPARATUS.

Application filed April 3, 1925. Serial No. 20,344.

To all whom it may concern:

Be it known that I, LOUIS KOOPERSTEIN, a citizen of the United States of America, residing in New York, county and State of New York, have invented certain new and useful Improvements in Soap-Dispensing Apparatus, of which the following is a specification.

This invention relates to soap dispensing apparatus of that type comprising a container for liquid soap and a valve by means of which a measured quantity of the soap may be discharged, the container being so arranged that the soap flows by gravity to the valve. The object of the invention is to provide a simple type of apparatus of this nature, wherein all of the valve members may as a single unit be assembled in and removed from the valve casing, and a double closure is provided by the valve element to prevent leakage from the reservoir through the valve.

The invention will be understood by reference to the accompanying drawing in which—

Figure 1 is a plan view of an embodiment of the invention, and

Figure 2 is a fragmentary vertical section through the same, the valve members being shown in detail.

Figure 3 is a transverse cross section on the line 3—3, Figure 2.

The embodiment of the invention illustrated in the drawing consists of a cylindrical container 1 for the liquid soap, the latter being provided with an intake 2 normally closed by a plug 3 which may be threaded in place or held by friction, as desired. The base of container 1 fits within a cup 4 formed as an upward extension of the valve body 5.

The valve body is formed with a rear extension 6 merging into a bracket 7, the latter being adapted to be secured upon a wall or other vertical support 8.

The valve body 5 is formed with two longitudinal chambers 9 and 10, the latter being of the greatest diameter. Chamber 9 communicates via opening 11 with the base of container 1, which is open, so that the liquid soap may flow, by gravity, into said chamber. Chambers 9 and 10 are normally shut off one from the other by a piston 12, this piston being carried by one end of a push rod 13^x, the latter carrying a thumb piece 14. Push rod 13^x is guided in its move-

ments by a block 15 which closely fits within chamber 10 and which is held in place by means of a plug 16 which is threaded within said chamber. Within chamber 10 and rearwardly of block 15 is a valve sleeve 17. 60 Sleeve 17 is formed with a peripheral, centrally disposed, channel 18 which communicates with a duct 19 leading to an inner circumferential channel 20 formed in the said sleeve.

Push rod 13^x is formed with a duct 21, which, when the parts are at rest, has an inlet at the rear of channel 20 of valve sleeve 17 and an outlet in front of channel 20, both inlet and outlet being closed by the inner 70 wall of said sleeve. Piston 12 is normally pressed against a washer 22 by means of a coiled spring 23 disposed within chamber 9. The valve body 5 is formed with a nozzle 24 having an opening 25 which 75 communicates with circumferential channel 18 formed in the valve sleeve 17.

In the operation of the device, rearward movement of push rod 13^x will carry piston 12 rearwardly until its forward end is in 80 advance of the wall *a* of opening 11, whereupon soap will flow in advance of the piston. In this position of the parts, soap would be permitted to flow directly from container 1 through the nozzle 24 were it not for the 85 fact that the outlet of duct 21 is closed by the wall of valve sleeve 17 rearwardly of inner channel 20. When the push rod is released, spring 18 will act upon piston 12, first, to close the opening in wall *a* and 90 thence to force the soap rearwardly of the piston through duct 21, which is momentarily opened by coming into communication with channel 20, the soap thence passing into duct 19, channel 18, out of the nozzle opening 25.

While, for convenience of illustration, port 19 is shown immediately above the nozzle opening, this position of the parts is not required, in view of the provision of channel 100 21.

It will be seen that all of the valve elements are removable as a unit from the casing by retracting screw plug 16, and that washer 22 may be expanded by screwing the 105 plug inwardly. It will also be seen that the outlet 20 is maintained closed by the push rod except when an operation of the rod momentarily establishes communication between duct 21 and channel 20.

2
Various modifications may be made in the embodiment of the invention herein shown without departing from the spirit of the invention, what I claim and desire to secure by Letters Patent being as follows:—

1. In soap dispensing apparatus, a valve body, two longitudinally extending chambers formed in said valve body, a piston normally disposed between the two chambers, a spring acting upon said piston, a push rod formed with a duct having an inlet and an outlet at the longitudinal surface of the rod, said rod being connected to the piston, a valve sleeve in the second chamber and affording a guiding member for the push rod, said valve sleeve having a duct normally intermediate the inlet and outlet of the push rod duct, a nozzle in the valve body, and a communication between said nozzle and the valve sleeve duct.
2. In soap dispensing apparatus, a valve casing provided with two longitudinal chambers, the second chamber being of greater diameter than the first chamber, a piston disposed between the two chambers and normally shutting them off from each other, a

push rod engaging the piston and formed with a duct having an inlet and an outlet on the outer surface of the rod, a valve sleeve within the second chamber and having a longitudinal aperture to receive the push rod said valve sleeve also having a duct extending transversely therethrough, a nozzle formed in the valve casing and communicating with the valve sleeve duct, and a screw plug threaded within said second chamber whereby the said valve elements may as a unit be secured within and removed from the casing.

3. In soap dispensing apparatus, a valve casing provided with two longitudinal chambers, a piston normally disposed between the two chambers, a push-rod formed with a duct having an inlet and an outlet in said rod, the said rod being connected in the piston, a valve sleeve surrounding said rod and the duct, a nozzle in the valve body, and a communication between said nozzle and the valve sleeve duct.

In testimony whereof, I have signed my name to this specification.

LOUIS KOOPERSTEIN.
